UNITED STATES PATENT OFFICE

MELVILLE C. CHAPMAN, OF FRAMINGHAM, MASSACHUSETTS

ADVERTISING DEVICE

Application filed October 5, 1928. Serial No. 310,558.

This invention relates to advertising devices of the intermittent rotary operable type.

An object of the invention comprehends a drum bearing advertising matter adapted to be exposed at predetermined intervals through a sight opening.

Another object of the invention contemplates an operating mechanism for the drum whereby the advertising matter may be shifted in juxtaposition to the sight opening.

More specifically stated the drum and operating means therefor are mounted within a cabinet of suitable design including the sight opening.

With the above and other objects in view, the invention further consists of the following novel features and details of construction, to be hereinafter more fully described, illustrated in the accompanying drawings and pointed out in the appended claims.

In the drawings:—

Figure 1 is a sectional view taken on line 1—1 of Figure 2.

Figure 2 is a sectional view taken on line 2—2 of Figure 1.

Figure 3 is a horizontal sectional view taken through the cabinet and drum on line 3—3 of Figure 2.

Figure 4 is a detail sectional view taken through a bracket mounting for a train of gears on line 4—4 of Figure 1.

Figure 5 is a detail sectional view taken on line 5—5 of Figure 1 through a stop mechanism for the drum.

Referring to the drawings in detail, wherein like characters of reference denote corresponding parts, the reference character 10 indicates generally a cabinet of any desired shape carried upon a base 11. A dome 12, carried upon the upper periphery of the cabinet, is adapted to close the uppermost end thereof.

A drum, having ends 13 and 14 respectively and common sides 15 of any number and shape, but in this instance are seven in number and of elongated shape to conform to the angularity of the ends and to the shapes of the outer surfaces thereof. A bearing 16, carried upon the upper side of the base 11

within the cabinet 10, is adapted to seat a companion bearing member 17 included upon the under surface of the end 13 of the drum and having connection with the lowermost projecting end of a standard 18 extended centrally of the longitudinal axis of said drum. The standard being keyed within each of the ends 13 and 14 to facilitate simultaneous operation therewith.

Seated upon the upper side of a shelf 19 horizontally disposed within the cabinet 10 above the end 14 of the aforementioned drum is the base member 20 of spaced parallel arms 21. Said arms are adapted to accommodate the enlarged end 22 of a bracket member 23 horizontally disposed from a motor 24. A pulley wheel 25, driven by the motor 24, drives a belt or other endless connection, such as indicated at 26, trained over a relatively large sheave 27. A spur gear 28, carried upon the lowermost projecting end of the shaft 29 for the sheave 27, is meshingly engaged with a complementary gear member 30, having a pinion gear 31 upstanding therefrom.

A relatively large ring gear 32, journaled upon an upstanding stub shaft 33, carried upon the upper side of the shelf 19 meshingly engaged with the pinion 31, is simultaneously operable in conjunction with a one tooth gear 34 adapted for selective engagement with a drum gear 35 keyed to the upwardly projecting end of the standard 18.

The side edges of each of the sides 15 are rolled, as at 36, to grippingly retain the adjacent side edges of placards 37 adapted to carry any desired advertising matter in the nature of pictures or printed matter. The cabinet 10 is in turn provided with a transparent panel 38 corresponding in size to that of the dimensions of the placards in order that the advertising matter carried by the latter may be effectively exhibited therethrough.

As evidenced by the illustration of my invention in Figure 1 of the drawings, it is noted that the one tooth gear 34 is adapted for selective engagement with the drum gear 35 whereby the latter will be turned the distance of two teeth each time the one tooth

of the gear 34 engages same. The distance of two teeth upon the drum gear 35 is equivalent to that of the width of one of the sides 15 for the drum, whereby the one tooth gear 34 5 will shift another of the placards behind the sight opening and panel in the cabinet each time the drum gear 35 is engaged.

An angle bracket 39, carried by and depending from the shelf 19, carries a curved spring finger 40 upon the depending extremity thereof. An enlargement 41, mounted upon the outer surface and adjacent the lowermost end of the curved spring finger 40, is adapted to frictionally engage the upstanding wall of a recessed portion 42 in the upper side of the end 14 of the drum. An adjusting element 43, horizontally disposed within the depending end of the angle bracket 39, is adapted for engagement at one end with the 10 inner side of the depending curved spring finger 40 to regulate tension of the latter against the upstanding wall of the recessed portion 42 in the upper side of the end 14 of the drum. The spring finger will prevent 15 the faces or sides of the drum from being shifted past the sight opening.

If desired, an incandescent lamp bulb may be included within the cabinet immediately above the sight opening therefor to illuminate the placards at night. By the same token, an intermittent switch may be included in circuit with the bulb to flash same each time another of the placards is exhibited.

The invention may be set up for use in 35 public squares and parks and other places of general interest where people are known to congregate.

The invention is susceptible of various changes in its form, proportions and minor 40 details of construction, and the right is herein reserved to make such changes as properly fall within the scope of the appended claim.

Having thus described the invention, what is claimed is:—

45 An advertising device comprising a cabinet having a sight opening in one side and a dome upon its top, a drum included within the cabinet having a shaft journaled within the bottom thereof, side portions for the drum being adapted for disposition in parallelism with that of the sight opening, gripping elements carried upon the side edges of the drum side portions to retain placards thereagainst, an operating mechanism included within the 50 cabinet and dome therefor being adapted to intermittently rotate the shaft to exhibit the placards through the sight opening, said drum having a recess within one end, a spring finger constituting a stop carried by and extending from the adjacent portion of the dome and projecting for an appreciable distance within the recess and frictionally engaging the upstanding wall of the latter, and an adjusting element for said finger whereby 55 the drum will be restricted as to movement 60 65 70 75 80 85 90 95 100 105 110 115 120 125 130

when disengaged from the operating mechanism to preserve alignment of the placards within the sight opening.

In testimony whereof I affix my signature.

MELVILLE C. CHAPMAN.
